DESIGN FOR JEWEL STUDDED SUN GLASSES

Laurence Colwell, New York, N. Y., assignor to
Revlon Products Corporation, New York, N. Y.,
a corporation of New York

Application January 15, 1946, Serial No. 125,558

Term of patent 7 years

(Cl. D57—1)

To all whom it may concern:

Be it known that I, Laurence Colwell, a citizen of the United States, residing in the city and State of New York, have invented a new, original, and ornamental Design for Jewel Studded Sun Glasses, of which the following is a specification, reference being had to the accompanying drawing, forming part thereof.

Fig. 1 is a front perspective view of jewel studded sun glasses, showing my new design; and
Fig. 2 is a rear perspective view thereof with the temples partly folded.

I claim:

The ornamental design for jewel studded sun glasses, substantially as shown.

LAURENCE COLWELL.
